UNITED STATES PATENT OFFICE

JAKOB SÜNDER, OF OBERURSEL, GERMANY, ASSIGNOR TO THE FIRM ADRIAN & BUSCH,
OF OBERURSEL, GERMANY

SHOE SEWING MACHINE

Application filed January 28, 1930, Serial No. 423,982, and in Germany January 28, 1928.

In the known shoe-sewing machines having a hooked-needle the take-up consists of a lever receiving an irregular swinging movement from a cam, a crank, or an eccentric. This drive by means of interconnecting levers has the disadvantage that it becomes worn out by the swinging mass and that for this reason the exact working of the machine is disturbed. According to the invention this drawback is obviated by the use of a rotary take-up in combination with shoe-sewing-machines having a hooked needle.

Rotary take-up devices are not new and have already been used in the common sewing-machines for textile fabrics. But all these known machines provided with a rotary take-up have an eye-needle. That means that the thread runs through a slot of the needle, whereas in machines having hook-needles the thread must be laid into the hook of the needle by comparatively intricate devices. It has therefore been an easy matter to provide the sewing machines working with eye-needles with a rotary take-up. But in machines having a hooked-needle not only the stitches are to be formed but the thread is also to be laid into the hook of the needle. This is obtained as known by the looper and the pull-off. As the looping can take place only during a part of the rotation of the machine it is evident that the movement of the several parts and the supply of the thread are in this case not uniform. This nonuniform movement has been obtained till now only by a swinging lever driven by a cam, crank or an eccentric.

The object of the present invention is to provide a rotary take-up which obviates the drawbacks of the swinging take-up and to deliver the thread to the stitch forming and to the looping devices in the exact amount required in machines having a curved hook-needle.

Other features of the invention will be apparent from the description of the illustrated embodiment thereof.

Fig. 1 is a side elevation of the thread take-up device at the beginning of the operative rotation of the disc. Fig. 2 is a front elevation of Fig. 1. Fig. 3 is a side elevation

of the thread take-up device showing the disc in operative rotation but advanced 180° from the position shown in Fig. 1. Fig. 4 is a front elevation of the thread take-up device at the end of the operative rotation of 55 the disc. Fig. 5 is a side elevation showing thread take-up device at the beginning of the inoperative rotation of the disc. Fig. 6 is a front elevation of Fig. 5. Fig. 1a is a fragmentary ground plan view of Fig. 2. Fig. 60 3a is a similar fragmentary ground plan view with the position of the various parts as shown in Fig. 3. Fig. 5a is a similar fragmentary ground plan view with the position of the various parts as shown in Fig. 5. 65

The take-up consists of a circular disk 1 fixed on the end of a shaft 3 journalled in the frame 2 of the machine. On the other end of the shaft 3 there is fixed a toothed-wheel 4 which is driven by means of the intermediate toothed-wheels 5 and 6 by the toothed-wheel 8 fixed on the main-shaft 7, see Figs. 1 and 2.

During one rotation of the machine the take-up-disk 1 makes two rotations, an operative one, see Figs. 1-4, and an inoperative one, see Figs. 5 and 6. On the take-up-disk there are arranged on fixed pins 9 and 10 thread-rolls 11 and 12. They serve for pulling down the thread thrown in a known manner around the bobbin case 13, for a quick locking of the stitch, and also for tensioning of the slack of the thread. The thread runs from the yielding auxiliary take-up 14 through an eye 15 of the thread carrier 16. 80

The thread carrier 16 is pivotally and axially movable in the fixed member 18 supporting the feeding body 17. The other end of the thread carrier 16 is in the form of a fork 19, which is connected to the front end of a 90 horizontally swinging feed-lever 21 by means of a pin 20. The feed-lever 21 is operatively connected to main shaft 7 by means of a cam disc 22 and a guide pin 24 to swing horizontally in a reciprocating manner, whereby upon each rotation of the main shaft, the swinging lever 21 and the connected thread carrying bolt 16 is given one complete reciprocating motion. As stated above during each rotation of the main shaft 7 the 100

disc 1 completes two rotations, in one of which the thread is in contact with the rollers 11 and 12 and one in which the thread does not contact the rollers. In order to prevent the roller 11 from contacting the thread before it is adjacent the member 16, an auxiliary take-up device 14 is provided, which holds the thread at an angle to the plane of the disc 1 (see Fig. 1a). The thread carrier 16 controls the position of the thread so that the thread comes into the path of the thread-rolls 11 and 12 (Figs. 1 and 2) during the operative rotation of the take-up-disk 1 or it is kept out of the path of the thread-rolls 11 and 12 (Figs. 5 and 6) during the inoperative rotation. The feeding body 17 is supported by and slides on the fixed member 18. The feeding body 17 is not connected to the thread carrier 16 but is actuated by means of the same grooved cam 22 and lever 21 by reason of its connection to lever 21 by means of the levers 28 and 29 (see Figs. 1 and 2). By the use of this separate lever connection a feeding stroke length may be selected independent of the length of the stroke of the thread carrier 16. Inasmuch as the thread carrier 16 and feeding body 17 are both actuated by the cam 22, they will both make a complete stroke at every revolution of the said cam.

The mode of operation of the rotary take-up is the following:

The work-piece is introduced into the machine in the known manner. The thread is looped in the common way when the needle has penetrated through the work-piece. When returning the needle draws the thread through the work-piece. A so called thread-divider brings by means of its hook the one thrum of the thread within the reach of the rotating shuttle so that the hook of the latter can catch this thrum and throw it over the bobbin accommodated in the shuttle.

While this is going on the rolls 11 and 12 which are suitably arranged on the take-up-disk 1 support the thread and deliver it (Figs. 3 and 4) or pull it down (Figs. 1 and 2) according to the requirements of the stitch forming tools. In order to prevent the thread from engaging the rolls 11 and 12 during the inoperative rotation of the take-up-disk 1, the thread carrier having the thread eye 15 is moved to the right out of the plane of the said rolls (see Figs. 5 and 6). During the operative rotation of the take-up-disk 1 the thread carrier returns into its primary position and lays the thread onto the rolls (Figs. 1 and 2) so that they are enabled to firmly lock the stitch and then to deliver the thread required for the next stitch (Figs. 3 and 4). As seen from Figs. 1a and 3 the auxiliary take-up is arranged with its thread-roll somewhat laterally to the plane of the thread-rolls 11 and 12. The roll 12 engages the thread at the beginning of the operative rotation of the disk 1. The roll 11, which

describes a much smaller circle than the roll 12 cannot contact the thread until it passes adjacent the thread carrier 16, due to the fact that the auxiliary thread take-up 14 is spaced laterally from the plane of the take-up disk 70 whereby the thread is passed from the member 14 to the thread carrier 16 at an angle to the plane of the take-up disk (see Fig. 1a). The roll 11 engages the thread only when passing the front half of its circular path. 75 From Fig. 5a it is to be seen that during the inoperative rotation of the disk 1 the thread is entirely out of reach of the rolls 11, 12.

What I claim is:

1. In a shoe sewing machine operating with 80
a lock stitch, a curved hook-needle, a uniformly
rotating disc having two take-up rolls
arranged approximately at opposite sides of
the axis and at different distances from the
axis of rotation of the disc, an auxiliary take- 85
up spaced laterally from the plane of the
take-up rolls, and means for presenting the
thread from the said auxiliary take-up to the
take-up rolls at an angle to the plane of the
said rolls. 90

2. In a shoe sewing machine operating with a lock stitch, a curved hook-needle, a uniformly rotating disc, two take-up rolls arranged approximately at opposite sides of the axis of the disc and at different distances from the axis of rotation of the disc, an auxiliary take-up, and a thread carrier movable laterally towards and away from the said disc and presenting the thread to the take-up rolls at different times from a position at an angle to the plane of the disc. 95 100

3. The combination with a rotating thread take-up of a sewing machine, thread engaging rolls carried by said take-up at opposite sides of the axis thereof, an auxiliary take-up 105 adjacent one side of the rotary take-up, a stitching mechanism adjacent the other side of the rotary take-up, and positioned whereby a thread passing thereto from the auxiliary take-up will extend across the rotary take-up 110 and laterally shiftable means movable towards and away from the rotary take-up and cooperating with the thread whereby said thread is presented to the rolls on every other rotation of the take-up. 115

4. The combination with a rotary thread take-up of a sewing machine, an auxiliary take-up to one side of the rotary take-up, a stitching mechanism to the other side of the rotary take-up, rolls carried by the rotary take-up at opposite sides of its axis, of means for shifting a thread laterally into the path of the rolls carried by the rotary take-up upon every other revolution of the said rotary take-up. 120

5. The combination with a rotary thread take-up of a sewing machine, an auxiliary take-up to one side of the rotary take-up, a stitching mechanism to the other side of the rotary take-up, thread engaging rolls car- 130

ried by the rotary take-up at opposite sides of its axis, means for shifting a thread into the path of the rolls on alternate rotations of the rotary take-up, said means comprising a slidably mounted shaft, through an aperture of which the thread extends, a driven member carried by the sewing machine, a rock lever carried by the shaft and a cam member carried by the driven member of the sewing machine and cooperating with the rock lever.

5 6. In a thread take-up device for sewing machines equipped with a hook needle, a uniformly rotating disc, take-up means on the disc and spaced from the axis of rotation of said disc and reciprocating means perpendicular to the plane of the disc for placing the thread on or removing it from the take-up means.

10 7. In a thread take-up device, a main drive shaft, a rotating disc operatively connected to said drive shaft and adapted to make two revolutions for one revolution of said drive shaft, take-up means on said disc, reciprocating thread carrying means cooperating with said take-up means to place the thread in contact with the take-up means at each alternate revolution of said disc.

15 8. In a shoe sewing machine operating with a lock-stitch, a uniformly rotating take-up means comprising a plurality of rolls continuously rotating in the same plane, and a means for moving the thread into and out of said plane, whereby the thread is alternately engaged and disengaged from said rolls.

20 9. In a shoe sewing machine as defined by claim 8, in which the said rolls are unequally spaced from the center of rotation 40 of said take-up means.

25 10. In a shoe sewing machine as defined by claim 8, in which the thread is moved into contact with the take-up rolls at alternate revolutions of the said take-up means.

30 45 In testimony whereof I affix my signature.

JAKOB SÜNDER.
